MOLDED PULP CUSHION PAD

William J. De Reamer, Crown Point, Ind., assignor to Mapes Consolidated Manufacturing Company, Griffith, Ind., a corporation of Delaware

Application May 6, 1947, Serial No. 746,385

3 Claims. (Cl. 217—26)

1

This invention relates to improvements in molded pulp cushion pads and it consists of the matters hereinafter described and more particularly pointed out in the appended claims. The pad of the present invention is especially adapted for use in connection with upper and lower conventional cellular fillers in a standard egg case. Generally it is of the kind illustrated and described in my prior Patent 2,414,724 of January 21, 1947, but includes improved structure having advantages that are not present in the pad of said patent.

One of the objects of the present invention is to provide a cushion pad of this kind, wherein the parts are so constructed and arranged relative to each other as to coact in materially stiffening the pad in every direction against bending, so that it not only has great strength, but will remain in a better unwarped flat condition in the handling it receives in use for its intended purpose.

Another object of the invention is to provide a pad of this kind wherein each area between each group of four of the adjacent seats thereof, is considerably stiffened and has the parts thereof arranged for better engagement upon the top edges of the intersections of the filler strips below so as to rest flatwise thereon and whereby in the building up of the several layers of fillers and pads, the pads remain in a better parallel relationship than possible in devices heretofore provided for this purpose.

Also, it is an object of the invention to so arrange the parts on the margin of the body outside the outermost row of egg receiving seats on said body, that said margins cannot readily curl or bend out of the plane of the body and whereby the pad as a whole will stack or nest better for shipment and may be better handled when packing an egg case therewith in connection with associated cellular fillers.

The above mentioned objects of the invention, together with others, as well as the advantages thereof, will more fully appear as the specification proceeds.

In the drawing:

Fig. 1 is a top view on a full size scale of the egg receiving side of a corner fragment of the improved pad, with a part of the cell forming filler used therewith appearing in dotted lines thereon.

Fig. 2 is a fragmentary view in side elevation of a number of pads disposed, with associated fillers between them, in a part of a standard egg case.

Figs. 3, 4 and 5 are detail vertical sectional views through parts of the pad fragment of Fig.

1 as taken on the lines 3—3, 4—4 and 5—5 respectively and on the scale of said Fig. 1.

Fig. 6 is a bottom view of a fragment of the pad showing parts in the vicinity of the line 4—4 of Fig. 1.

Referring now in detail to that embodiment of the invention illustrated in the drawing, the improved pad, which is made of molded pulp material, is a scant 11½" square and is of a uniform stock thickness throughout, on the order of $\frac{1}{8}$ of an inch. It includes a flat sheet-like body 10 with egg receiving seats 11 rising from the upper surface thereof. The seats, which are herein shown as of an octagonal shape, are arranged in longitudinal and transverse rows that parallel the longitudinal and transverse edges of the body. There are six of such seats in each row so that each pad has thirty-six seats. These seats are so arranged as to match up or register with each cell 12, as formed by the intersecting strips 13 and 14 respectively of the fillers, with which the pads are employed in a standard egg case, a part of which appears in Fig. 2 and will be later mentioned.

Each egg receiving cup or seat 11 includes alternate and intermediate pairs of inner and outer walls 15—15a and 16—16a respectively, which converge toward the top to join as a ridge 17. The inner walls 15 and 16 of said pair of walls extend inwardly and downwardly from said ridge 17 and join with a rectangular bottom 18 for each cup or seat, which bottom is disposed in a plane above that of the body 10, as best appears in Fig. 3.

The outer side walls 15a of each alternate pair of most of the seats on the pad extend downwardly and outwardly from the ridge to merge into filler strip edge supporting portions 19 disposed in a plane between that of said seat bottoms 18 and said body 10. These portions 19 between the various seats 11 are relatively long with respect to their width and they extend in the directions of the associated filler strips 13 and 14 respectively, as best appears in Fig. 1.

Between the wall portions 16a of each group of four adjacent seats 11 is an area 20, preferably square in shape, the bottom of which is disposed in the plane of the body 10, as best appears in Fig. 4. The center of each area is arranged coincident with the associated intersections of the filler strips 13 and 14. The outline edges of each square area 20 is defined by the base of said wall portions 16a and each area is crossed by diagonally extending intersecting hollow ribs 21—21, the ends of which merge into said wall portions. The top edges of said ribs are disposed in the plane of the portions 19. Thus these ribs ex-

tend at an angle to the strip edge supporting portions 19 so that in no place in the pad is there a bending plane that is not interrupted by the ribs mentioned. Thus the pad cannot readily be bent in a straight line in any direction of the pad and it is thereby materially stiffened and reinforced in strength.

On the margin of the body 10 outwardly from the wall portions 15a in the outermost rows of seats are triangular extensions 22—22, the apex or pointed ends of which terminate substantially at the edge of the pad, as best appears in Fig. 1. Each extension 22 has a flattened top 23 that is disposed in the plane of the portions 19 and the top surfaces of the ribs 21 and these flattened tops form the supports for portions of the outermost strips 13 and 14 of the filler. Each top 23 is triangular in shape and its base joins the bottom edge of the associated wall portion 15a.

On the margin of the pad body are provided cruciform hollow ribs 24—24, one arranged in line with the rows of portions 19 in both directions of the pad and in each corner of the margin is another cruciform rib 25. The inner end parts of each rib 24 join the wall portions 16a—16a of the outermost seats about the pad and the inner end part of each rib 25 joins that part of each seat as formed by the diagonal sides of the triangular portions of each seat in each corner of the pad. The intersection of the parts forming the ribs 24 and 25 respectively are so disposed as to register with the intersections of the outermost strips 13 and 14 of the fillers used with the pads and the top surface of said ribs are disposed in the same plane as that of the top surface of the ribs 21—21 and the portions 19—19.

In Fig. 2 is illustrated a fragment of a pack comprising the improved pads and associated fillers when disposed in a part of the standard egg case 26, the bottom of which is indicated at 27 and one end of which is indicated at 28.

In arranging a pack, as mentioned, one of the improved pads is placed in one of the compartments of the egg case, with its body 10 engaged on the bottom 27 of the case, as in Fig. 2. The parts of the body engaged in supporting relation upon said bottom are the margin thereof and the squared areas 20. A cellular filler composed of sets of the intersecting strips 13 and 14 in its opened up condition, is then placed in the case, with the bottom edges of said strips between the intersections thereof, engaged in supporting relation upon the portions 19 of the pad and with the intersections of said strips resting in supporting engagement upon the intersections of the hollow ribs 21—24 and 25. Portions of the bottom edges of the outermost strips, between their intersections, will rest in supporting engagement upon the flat tops 23 of the triangular extensions 22.

An egg E is placed in each cell 12, preferably small end down, which end will engage at eight points or areas on the inner walls 15 and 16 of the associated seat, the meeting corners of said walls providing air circulating channels about that end of the egg engaged in said seat.

After eggs have been placed in all cells of the filler associated with the first pad, another pad is placed upon the top edges of the strips of said filler with the bottom surfaces of the four sections of each area 20, as well as marginal parts 70 of the body 10 in line therewith, engaged in supporting relation directly upon the top edges of said fillers adjacent the intersections thereof. This will dispose the intersections of each of the ribs 21—24 and 25 in line with said intersections.

In this respect it is pointed out that while the underside of said ribs, which are hollow, form downwardly appearing grooves, they extend diagonally with respect to said strips so that the strips cannot enter the same. The areas mentioned as engaged upon the strips as described, are of sufficient size and number so that the strips cannot cut through the same under the weight of the eggs on the pads above. Also, with this arrangement of said areas and the ribs as described, the pad remains in a flat condition against warping in the drying out the pads receive in the manufacture thereof.

Additional sets of intersecting fillers and associated pads are used until there are five layers of eggs, with thirty-six eggs per layer. At the top of the stack a final pad is positioned preferably with the egg seats facing upwardly. However, under certain conditions, such as for example 15 when the eggs in the top layer are relatively small, the upper pad may be inverted, i. e. with the egg seats 11—11 facing downwardly.

With the structure described, the bottom margin of the strips of each filler are disposed 25 upon the portions 19 of the pad and are then prevented from shifting. In the present instance, the upper margins of the strips of the filler do not have an interlocked engagement with the bottom of the pad above, the pad resting in supporting 30 engagement upon said edges by reason of the four sections of each area 20 and those marginal parts of the body in line therewith. These sections present a considerable area and will rest flatwise upon the edges of the filler below and as the sections mentioned afford the effective bottom for 35 the pad as a whole, the pad cannot rock or skew when placed in the egg case, but immediately finds its seat upon the filler, upon which it is placed. Thus each pad naturally finds a position parallel with those previously placed in the case so that the stack as a whole is evenly built up with all pads in parallelism.

Furthermore, all of the projections and the grooves or hollow areas provided thereby are of 45 such size, form and disposition that a number of the pads may be readily stacked or nested for shipment to the place where they are to be used. They can then also be readily separated without injury to the pads.

While in describing my invention I have referred in detail to the form, construction and arrangement of the parts involved, the same is to be considered only in the illustrative sense and therefore I do not wish to be limited thereto except as may be specifically set forth in the appended claims.

I claim as my invention:

1. A molded pulp cushion pad for use in connection with upper and lower fillers comprising intersecting cell forming strips, said pad having a rectangular sheet-like body with egg receiving seats projecting above and spaced in longitudinal and transverse rows on the upper face of said body portion to register with cells formed by the fillers, each seat including inner and outer oppositely inclined walls that join as a ridge for the top of the seat, the inner wall of each seat affording support for the egg engaged thereon, parts of the body portion between certain outer wall portions of adjacent seats providing upwardly opening channel-like portions for receiving and holding against lateral shifting marginal bottom portions of the strips of the upper filler between the intersections thereof, other parts of 65 said body portion, each being bounded by other

wall portions of each group of four adjacent seats, each of said other parts being formed in its bottom with downwardly opening channels that extend substantially at a right angle to each other in opposite directions diagonally of the body and dividing each of said other parts into four spaced portions, the bottoms of which are disposed in the plane of the body and are adapted to engage for support upon upper edge portions of the strips of the filler below, adjacent the intersections thereof.

2. A molded pulp cushion pad for use in connection with upper and lower fillers comprising intersecting cell forming strips, said pad having a rectangular sheet-like body with egg receiving seats projecting above and spaced in longitudinal and transverse rows on the upper face of said body portion to register with cells formed by the fillers, each seat being of octagonal shape and including alternate and intermediate pairs of oppositely inclined inner and outer walls that join as a ridge for the top of each seat, the alternate outer walls of each seat extending parallel with the edges of the body portion and the intermediate outer wall portions of each seat extending diagonally relatively to said edges, the inner walls of each seat affording points of support for the egg engaged thereon, parts of the body portion between alternate outer walls of adjacent seats providing upwardly opening channels for receiving and holding against lateral shifting marginal portions of the strips of the upper filler between intersections thereof and other parts of said body portion between the first mentioned parts being bounded by associated intermediate outer wall portions of each group of four adjacent seats, each of said other parts of said body portion being formed to provide downwardly opening channels that extend in substantially opposite diagonal directions and divide each of said other parts of the body portion into four spaced portions, the bottoms of which are disposed in the plane of said body and which four spaced portions are adapted to engage for support upon upper edge portions of the strips of the filler below, adjacent the intersections thereof.

3. A molded pulp cushion pad for use in connection with upper and lower fillers comprising intersecting cell forming strips, said pad having a rectangular sheet-like body with egg receiving seats projecting above and spaced in longitudi-

nal and transverse rows on the upper face of said body portion to register with cells formed by the fillers, each seat including inner and outer oppositely inclined walls that join as a ridge for the top of the seat, the inner wall of each seat affording support for the egg engaged thereon, parts of the body portion between certain outer wall portions of adjacent seats providing upwardly opening channel-like portions for receiving and holding against lateral shifting marginal bottom portions of the strips of the upper filler between the intersections thereof and other parts of said body portions, each being bounded by other wall portions of each group of four adjacent seats, each of said other parts being formed in its bottom with downwardly opening channels that extend substantially at a right angle to each other in opposite directions diagonally of the body and dividing each of said other parts into four spaced portions, the bottoms of which are disposed in the plane of the body and are adapted to engage for support upon upper edge portions of the strips of the filler below, adjacent the intersections thereof, 15
